CHARLES F. STODDARD, OF NEW YORK, N. Y., ASSIGNOR TO AMERICAN PIANO COMPANY, OF NEW YORK, N. Y., A CORPORATION OF NEW JERSEY.

AUTOMATIC MUSICAL INSTRUMENT.

1,409,495.

Specification of Letters Patent. Patented Mar. 14, 1922.

Application filed March 30, 1917, Serial No. 158,593. Renewed December 19, 1921. Serial No. 523,588.

To all whom it may concern:

Be it known that I, CHARLES F. STODDARD, a citizen of the United States of America, and a resident of the city of New York, in the county and State of New York, have invented an Improvement in Automatic Musical Instruments, of which the following is a specification.

This invention relates to automatic means for playing musical instruments, such as pianos, and pertains more particularly to means for governing and varying tone intensities.

Among other objects the invention provides apparatus for varying the normal pressure of the main source of power. Such apparatus may be combined with expression governing and regulating mechanism which, if desired, may have the capacity for producing incremental changes in playing intensities, for maintaining uniformity of any given playing intensity whether one or many notes are simultaneously sounded, and for producing substantially continuous progressive changes in playing intensities.

In the type of instrument to which this invention may find its more general application, the pressure of the main source of power is usually maintained substantially constant, while variations in playing intensities are generally obtained by varying the influence exerted upon the playing pneumatics by the constant pressure of the main source of power. This is usually accomplished through the agency of a throttle valve which controls communication between the main source of power and the playing pneumatics.

For illustration the accompanying drawings show one practicable embodiment of the invention which employs suitable pneumatically governed devices in cooperation with a piano action, but obviously the invention is susceptible of embodiment in various constructions other than that particularly shown and described herein. It will also appear that it is not indispensable that the invention be used in the particular combination herein shown and described for illustration since its substantial advantages may exist in combination with other suitable mechanism.

The single figure of the drawings is a diagrammatic representation of a typical player action with operating and governing means

which exemplifies the application and utility of the invention.

Referring to the drawings a striker or player pneumatic 1 is provided having a sticker 2 to act upon a wippen 3 and thereby operate the usual piano action as well understood in the art. A wind trunk 7 leads to a wind chest for the player pneumatics each of which has a secondary valve 8 controlled by a primary valve 9 operated from a tracker board T through a duct 10 in the usual manner.

The trunk 7 communicates with a regulated exhaust chest 12, which may be of any practicable construction. A high exhaust chest 14, arranged for communication with chest 12 may be connected by a trunk 15 with any practicable source of pneumatic exhaust such as an illustrative pumping mechanism generally denoted by 16.

For purposes of illustration and explanation the apparatus of the drawings has been selected. Therein the striker pneumatics 1 are caused to operate by the regulated exhaust in chest 12. In order to vary the operation of the striker pneumatics this regulating exhaust may be varied by subjecting it more or less to the influence of the high exhaust in chest 14. For this specific purpose aforesaid, a port 30 controlled by a throttle valve 31 is provided between the high exhaust chest 14 and the regulated exhaust chest 12.

This valve 31 may be operated by any suitable means, preferably by apparatus of the general character of that herein illustrated. In this specific apparatus the stem 32 of the valve 31 is connected to a movable board 33 of a bellows apparatus presently described; said board being hinged at 17. Such apparatus has a three-fold capacity for controlling the valve 31. It automatically produces incremental changes in playing intensities; it performs a regulating function, that is, it maintains any given playing intensity whether one or many notes be sounded; and it automatically produces continuously progressive changes in playing intensities for crescendo and diminuendo purposes. In addition to the means for controlling playing intensities through the agency of the valve 31, further means, to which this invention is more particularly directed, are provided to control or vary the pressure of high exhaust and thereby give 110

the apparatus a further capacity for varying playing intensities.

Following a brief description of the apparatus acting through the bellows board 33, the embodiment of the further means referred to will be described. As the description proceeds it will be obvious that the invention is not dependent upon the specific details of construction, or the specific mode of operation of the apparatus herein described.

Assuming for the present that the pressure of the main source of power is maintained substantially uniform, the three capacities of the apparatus acting through the bellows board 33 will be briefly described in the sequence heretofore indicated.

Beneath the board 33 are three bellows 34, 35 and 36 which have their upper boards secured to the common movable board 33 and their lower boards secured to a fixed plate 18.

Another bellows 37 has its lower board secured to the movable board 33 and its upper board to a stationary plate 38. A condition of partial exhaust is maintained at all times in the bellows 37 as presently described. The degree of exhaust in bellows 37 may be varied but for the present this capacity may be disregarded and the pressure within the bellows acting upon the board 33 may be considered uniform. Thus, the pressure in the bellows 37, being always less than atmospheric pressure, said bellows in effect exerts continuously uniform upward pull on the board 33 contributing to control the valve 31.

Ducts 40, 41 and 42 enter respectively the bellows 34, 35 and 36. Each duct may be controlled by any practicable valve mechanism to admit to its bellows either atmospheric pressure, or regulated pressure from the chest 12; and regulated pressure may be admitted to the bellows selectively while atmospheric pressure will be present in these bellows, if any, which do not contain regulated pressure. Another regulated pressure is present in any one or more of the bellows 34, 35 and 36 the effect thereof is to produce a downward pull upon the board 33. This downward pull is opposed by the upward pull which results from the condition of partial exhaust in the bellows 37 the two contributing to control the valve 31. High exhaust in the chest 14 exerts some downward pressure upon the area of the valve 31 itself; and regulated pressure in the chest 13 exerts some upward pressure upon the area of the valve.

Since the regulated pressure is usually greater, it generally predominates and the resultant upon the valve itself is an upward pressure which combines with the resultant of the pressure in the several bellows to complete the control of the valve 31.

The construction and arrangement of the

apparatus may be such that the opposed upward and downward acting forces control the valve and tend to hold it in a balanced condition. For example, if regulated pressure be present in all three of the bellows 34, 35 and 36, the downward pull of these bellows upon the board 33 is at its maximum and tends to close the valve 31 and minimize the opening between the chests 12 and 14. Under these circumstances, playing intensities, as controlled by this portion of apparatus, will be at the minimum. The bellows 34, 35 and 36 will then operate substantially as a single regulator pneumatic for maintaining a uniform degree of exhaust in the regulated pressure chest whether one or many notes are concurrently sounded. A substantial uniformity of playing intensities will thereby be maintained.

The bellows 34, 35 and 36 may be governed to vary playing intensities by varying the downward acting force which they contribute to the control of valve 31. If atmosphere be admitted to the bellows 36, for example, the aggregate pull on the board 33 is relaxed to some extent. To restore the condition of balance the degree of regulated exhaust acting upon the board 33 through bellows 34 and 35 will be permitted to increase. Therefore the apparatus will operate to regulate playing intensities at a higher level.

Regulated pressure or atmosphere may be admitted to the several bellows 34, 35 and 36 selectively or in combination. To those skilled in the art, it will be readily understood that several well defined grades of playing intensity may thereby be established.

Upon admitting atmosphere to all the bellows 34, 35 and 36, the forces acting upward upon the valve 31 will so far predominate as to open the valve to enlarge communication between the chests 12 and 14 to the maximum.

Any suitable means may be adopted to govern that part of the regulating mechanism which operates through bellows 34, 35 and 36 to initiate different substantially distinct grades of regulation. Herein the duct 40 connects the bellows 34 with a valve chamber 50 having a port to atmosphere and a port to a chamber 60 which is connected to the regulated pressure chest 12 through a passage 61. A duplex valve 51 is mounted in valve chamber 50 and is controlled by a diaphragm 52 of a diaphragm chamber 53. A duct 54 leads from said diaphragm chamber to a vent in the tracker T correspondingly numbered. The parts 50-55 described in connection with duct 40 are triplicated for ducts 41 and 42, the corresponding parts of the valve mechanism for the latter being indicated by the numerals 50, 51, etc., with indices *a* for the valve 130

mechanism for duct 41, and *b* for the valve mechanism for valve 42.

The manner in which the valves 51, 51^a and 51^b may be controlled from the tracker 5 will be sufficiently obvious to those skilled in the art so that a detailed description is unnecessary. Suffice it to say that when any one of the tracker vents is opened to atmosphere the bellows corresponding there- 10 to will also be opened to atmosphere, and when a tracker vent is closed to atmosphere its corresponding bellows will be opened to regulated exhaust.

The preceding description has been de- 15 voted to an illustrative form of apparatus by which substantially distinct grades or degrees of regulated exhaust may be established for playing notes at substantially distinct grades of intensity. In an apparatus 20 of the character described, it is preferable that the upward pull on the board 33 be maintained substantially uniform. For this purpose the preferred embodiment of the apparatus utilizes a pneumatic system, about 25 to be described, which exerts a pneumatic pull through the bellows 37 in opposition to the bellows 34, 35 and 36; said pneumatic pull being maintained substantially uniform and corrected when necessary. For con- 30 venience in that part of the description immediately following, the capacity of the apparatus to produce incremental changes in playing intensities may be disregarded and it may be assumed that regulated ex- 35 haust is present in all the bellows 34, 35 and 36 with the result of a maximum downward pressure on the board 33 and valve 31.

The bellows 37 is connected by duct 100 with a pneumatic 101. A spring 102 is fastened to the movable board of pneumatic 101 and to an adjustable screw 103 threaded in a block 104. A stop 105 is provided to limit the expanding movement of the pneumatic 101.

45 The pneumatic 101 may be exhausted through a duct 106 opening to a valve chamber 107 having a port 109 to atmosphere and a port 110 to an exhaust chamber 111, preferably connected to high exhaust. A valve 50 112 is mounted in chamber 107 and is controlled by a diaphragm 113 of a diaphragm chamber 114. Diaphragm chamber 114 may be exhausted through a bleed 115 and atmosphere may be admitted thereto through 55 a duct 116 and port 117. The opening of the port 117 is controlled by a valve 118 and as will be readily understood the effective opening of this port relatively to the size of the exhaust bleed 115 will control 60 the operation of the diaphragm 113 and valve 112, which in turn controls the degree of exhaust in pneumatic 101 and bellows 37.

Communication between the pneumatic 65 101 and valve chamber 107 through duct

106 is somewhat restricted by an adjustable screw 119 which slightly retards the action of the valve 112 upon the pneumatic 101. Upon a slight fluctuation in the degree of exhaust in the pneumatic 101 the valve 112 70 is automatically operated, as hereinafter described, to restore, thereby in effect maintaining, the degree of exhaust the same substantially uniform. This restoration will be slightly retarded and rendered more delicate 75 and refined because of the interposition of the obstruction screw 119.

For the purpose of more rapidly restoring the intended normal pneumatic condition of pneumatic 101, a second adjustable obstruc- 80 tion screw 120 is likewise interposed between the valve chamber 107 and the pneumatic 101 and a by-pass around the screw 119 is provided by passages 121 and 122. When it is desired to compensate for an extreme fluctuation in the pneumatic condition of pneumatic 101, the by-pass 121—122 may be opened. By-pass 121—122 may be closed by a valve 123 mounted upon a diaphragm of a diaphragm chamber 124. This chamber is 90 connected by a duct 125 with a valve chamber 126 having a port 127 to atmosphere and a port 128 to exhaust chamber 111. A valve 129 controls ports 127 and 128. Normally valve 129 is seated to close exhaust port 128 95 and open atmosphere port 127 thereby admitting atmosphere to duct 125 and diaphragm chamber 124. This permits valve 123 to be normally seated to close by-pass 121. Upon an extreme fluctuation of the 100 pneumatic condition in the pneumatic 101, the valve 129 is automatically lifted to exhaust diaphragm chamber 124 and open by-pass 121—122, thus permitting a more rapid flow of air along duct 106.

105 The valve 129 is governed by diaphragm 130 of a diaphragm chamber 131 which communicates by a duct 132 with a port 133 adjacent the port 117, the port 133 being controlled by the valve 118. The usual exhaust 110 bleed for diaphragm chamber 131 is provided by a bleed passage 134.

The valve 118 is operated by an arm 137 projecting from the movable board of the pneumatic 101 and is so arranged that the 115 port 117 will be first opened to operate valve 112 and thereby correct a variation in the pneumatic condition of pneumatic 101. Only thereafter if the expansion of the pneumatic 101 is sufficiently great, will port 120 133 be opened to cause a more rapid correction of the intended normal pneumatic condition.

The pneumatic 101 is controlled in its movements by the differential between the 125 pull of the spring 102 and the action of the exhaust within the pneumatic. With the described arrangement of valves, these opposed forces tend to hold the pneumatic 101 in balance. For example, the pneumatic 130

4

tends to collapse to that point at which the atmosphere bleed 117 is maintained at such a capacity that the degree of exhaust in the diaphragm chamber 114 holds the valve 112 in that position in which the relative exhaust and admission of atmosphere past the valve 112 determines a degree of exhaust within the pneumatic 101 which just balances the pull of the spring 102. Any influence tending to disturb this condition of balance will be promptly compensated so that the ultimate effect is to maintain within the regulator tension system a substantially uniform degree of exhaust which, as will appear to those skilled in the art, will be determined ultimately by whatever tension may be given to the spring 102 by its original adjustment. The mechanism which intervenes between said spring and the regulating pneumatics effectually eliminates the objections to the use of a mechanical spring and serves to transmit the action of said spring in such a way as to refine the regulation and render it extremely accurate. Furthermore, it is preferred that the effective area of the pneumatic 101 be somewhat greater than that of bellows 37 so that the expanding and collapsing movements of the pneumatic 101 (in response to similar movements of the bellows 37) are much less in extent. With such an arrangement the minimized movements of the pneumatic 101 produce only slight elongations and contractions of the spring 102 and therefore produce only minimum changes in the tension of the spring.

That part of the apparatus just described, in addition to its capacity for maintaining substantial uniformity of tension upon the regulator pneumatic (herein exemplified by bellows 34, 35 and 36,) also possesses the capacity of varying playing intensities by varying the upward pull on the regulator and of controlling this variation at different speeds.

45 If the pneumatic 101 is collapsed beyond its position of normal self-adjustment the spring 102 will be elongated, thereby increasing its tension and causing an accompanying increase in tension of the air condition in pneumatic 101 and bellows 37. This will result if the valve 112 is raised and held in raised position for a substantial length of time, that is, until the pneumatic 101 is completely collapsed. Air will be withdrawn 50 from pneumatic 101 through the small opening formed by the obstruction screw 119 and an increase in tension will therefore take place at a relatively slow speed.

This operation of the pneumatic 101 ultimately causes a slow increase on the upward pull of the movable board 33 and such a variation of one of the forces controlling the valve 31 causes a slow continuously progressive increase in playing intensities.

65 If the valve 112 is lowered to close port

110 and open port 109, atmosphere will be admitted to pneumatic 101 past obstruction screw 119 and permit a slow restoration of the pneumatic 101 to its normal position. This operation slowly decreases the upward 70 pull on the board 33 with the ultimate result of a slow continuously progressive decrease in playing intensities.

If the valve 129 is raised simultaneously with valve 112 the pneumatic 101 will be 75 collapsed at a greater speed, due to the opening of the by-pass 121-122. If thereafter valve 112 is lowered and valve 129 held in raised position pneumatic 101 will quickly expand. These two operations result re- 80 spectively in a fast, continuously progressive increase or decrease in playing intensities.

Such changes in playing intensities as are described in the preceding paragraphs are 85 commonly termed crescendo and diminuendo effects.

The above described operations of the valves 112 and 129 for producing crescendos and diminuendos may be controlled by any 90 practicable means. For illustration, the diaphragm chamber 114 may be connected to the tracker by a duct 138 opening to a tracker vent correspondingly numbered which may be opened or closed by perforations in a music sheet. The diaphragm chamber 131 may be similarly connected to the tracker bar by a duct 139. As will be readily understood by those skilled in the art the regulating mechanism may thus automatically produce crescendos and diminuendos at different speeds under the control of a note sheet.

The manner of properly coordinating the several parts of the regulating mechanism 105 under the control of a perforated music sheet will be sufficiently obvious to those skilled in the art and need not be described in detail herein.

The apparatus heretofore described provides means for increasing playing intensities from a predetermined minimum to a maximum which is dependent upon the pressure established at the main source of power. In other words, specifically referring 110 to the apparatus heretofore described, the valve 31 may be controlled to increase the degree of exhaust in chest 12 by substantially distinct increments or by substantially continuous progression at different speeds, 115 maintaining all the while uniformity of playing intensities whether one or many notes are concurrently sounded.

It is oftentimes desirable in the type of instrument to which this invention more particularly relates, that is to say, an instrument adapted for the mechanical reproduction of the manual renditions of skilled pianists, to have available for use from time to time a greater force for the operation of 120

the player pneumatics than it would be advantageous or desirable to maintain continuously in the mechanism. The continuous maintenance by the pumping mechanism 5 of the highest pressure which could be advantageously used, might eventually weaken the instrument and result in a more or less serious impairment of its accuracy and refinement of operation.

- 10 When producing the finer shades of intensity changes during the playing of a composition with pianissimo effect, refinements of operation can be more effectively obtained if the difference between the pressure of high 15 exhaust and the pressure of regulated exhaust is not too great. During the playing of notes with pianissimo effect a very slight variation in the degree of regulated exhaust is immediately noticeable in the playing intensities, and therefore at such times the apparatus may be adjusted to produce smaller increments of change. As the reproduction of a composition approaches fortissimo effect, slight changes in the degree of regulated exhaust are not as noticeable. Therefore, to produce an audible variation during fortissimo playing greater changes must be made in the degree of regulated exhaust. Furthermore it will be readily understood 25 that the effectiveness of the reproduction of a composition depends to a great extent upon the contrast between the lowest and highest playing intensities which may be inaugurated by the pressure governing apparatus.

With these and other facts in mind, means are herein provided for automatically increasing the degree of exhaust maintained by the main source of power, if and when 40 it is desired to have a greater power available for the operation of the striker pneumatics. The specific apparatus embodying this invention which is herein shown for purposes of illustration, will be presently 45 described; and it is preferably, though not essentially, made dependent upon the main expression governing mechanism which operates through bellows board 33. Means may also be provided for manually or automatically rendering the presently described 50 apparatus continuously inoperative or placing it in readiness for operation when conditions require.

Referring again to the drawings, the main 55 source of power 16, which may be of any preferred construction, is herein illustrated as a number of exhauster bellows 300, arranged radially about a shaft 301 which is journalled in suitable bearings within a casing 302. A drive wheel 303 is fast to the shaft 301 and the pumping mechanism is preferably operated from an electric motor M through a belt 304. A crank arm 305 is fast to the shaft 301, and concentrically journaled upon a crank pin 306, are connecting

rods 307 which, at their opposite ends, are journalled to the movable boards 308 of the respective exhauster bellows 300. Each bellows 300 is provided with inlet ports 309, which open to a common wind chest 310 and 70 are controlled by flap valves 311. Outlet ports 312 are formed in the movable boards of the exhauster bellows, and are controlled by flap valves 313.

A governor or reservoir bellows 351 is 75 placed in communication with the high exhaust chest 14 conveniently through wind trunk 15, wind chest 310 and a port 350. This bellows has a movable board 352 and a stationary board 353. A spring 354 is attached to the movable board and at its other end is fast to an adjusting screw 355 threaded in a bracket 356.

An atmosphere port 357 is provided for the reservoir bellows and preferably located 85 in the movable board 352. A valve 358 commonly called a spill-valve, mounted upon a threaded stem 359 and conveniently held in position by arms 360 and 361, is adapted to open or close the port 357 as occasion may 90 require. A light spring 362 contributes to hold the valve in closed position. During the operation of the reservoir bellows the differential between atmospheric pressure on the outside of the valve and the pressure of 95 exhaust upon the inside of the valve, also contributes to control the valve. The resultant force tends to hold the valve in closed position.

The pumping mechanism is driven at a 100 substantially constant speed and therefore has the capacity for exhausting air from the wind chest 310 at a substantially constant speed. Air may flow into the chest 310 from two general sources, (1) from the player 105 mechanism (including all parts of the instrument which are required to be operated by withdrawing air therefrom or decreasing the pressure of the contained air) and, (2) through the reservoir bellows 351. It is ob- 110 viously immaterial to what part of the apparatus the reservoir bellows is connected, because its operation and effect will be substantially the same if connected to any part of the high exhaust system between the 115 throttle valve 31 and the pumping mechanism.

The amount of air drawn from the player 120 mechanism generally varies from time to time according to the amount of atmosphere admitted during the operation of the instrument. If means are provided for admitting atmosphere from another source (herein exemplified by the spill-valve in the reservoir bellows) this second source of atmosphere 125 may be automatically varied to compensate such variations and make up with the air drawn through the player mechanism substantially the full capacity of the pumping mechanism. By suitable means, hereinafter 130

illustrated, the second source of air may be so controlled that it will admit atmosphere only when a predetermined tension has been attained in the high exhaust system and will thereafter maintain a substantially constant degree of tension therein. If the action of the atmosphere port or spill-valve is varied, the tension throughout the high exhaust system may also be varied.

10 Ordinarily a variation in the degree of high exhaust will have slight effect upon regulated exhaust and upon playing intensities in view of the fact that the pressure of high exhaust upon the upper side of regulator valve is a relatively small factor in the balancing equation controlling that valve. If, however, the degree of regulated exhaust is caused to approximate the normal degree of high exhaust by opening the regulator 15 valve to its full capacity a variation in high exhaust may be effective to vary playing intensities.

Disregarding for the moment the capacity of the apparatus to vary the degree of high exhaust, the manner in which high exhaust is governed to maintain a normal substantially uniform pressure will be first described.

The capacity of the pumping mechanism 30 for exhausting air from the player mechanism is generally sufficient to predominate over any normally possible admission of air thereto. Therefore the reservoir bellows will be partially exhausted. The differential between atmospheric pressure acting upon the outer surface of the movable board 352 and the pressure within the bellows will cause the reservoir bellows to collapse somewhat and thereby elongate and tension the spring 354. As the reservoir bellows collapses the stem 359 of the spill-valve 358 will contact with an abutment 363, herein shown as the movable board of a pneumatic 364. Assuming that the abutment 363 is fixed, the 40 spill-valve 358 will be opened more or less to admit atmosphere to the reservoir bellows as required to maintain the movable board 352 in a substantially stable position at a point where the spring 354 is somewhat elongated. Under these circumstances the tension of the spring 354 will govern the degree of exhaust within the reservoir bellows and consequently the tension throughout the high exhaust system.

55 When substantially no air is being admitted to the chamber 310 from the player mechanism, the spill-valve 358 will be opened widely to permit substantially the entire amount of air exhausted by the pumping mechanism to be drawn through the port 60 357, the reservoir bellows 351 and port 350.

If the amount of atmosphere admitted through the playing mechanism increases, the tension of high exhaust may decrease 65 slightly and permit the reservoir bellows 351

to expand somewhat thereby closing more or less the spill-valve 358 and decreasing the amount of atmosphere admitted through port 357. In this manner, as will be understood by those skilled in the art, the reservoir 70 bellows maintains a substantially constant tension on high exhaust, the opening of atmosphere port 357 being automatically varied as required. Furthermore it will also be readily understood that the tension of 75 high exhaust determinable by the reservoir or governor bellows is dependent upon the tension of the spring 354. For convenience the tension so governed may be termed the normal minimum degree of exhaust main- 80 tained by the main source of power.

This normal minimum tension of high exhaust is preferably adjustable and adjustment may herein be made through the spring 354 by means of the screw 355, or 85 by varying the length of the spill-valve stem 359 by turning the valve on the threaded portion of its stem to cause the valve to operate when the movable board is nearer the abutment for a higher tension, or further 90 away from the abutment for a lower tension. In either case the ultimate adjustment of the tension of high exhaust is dependent upon the tension of the spring acting upon the reservoir.

95 The manner in which the desired normal minimum tension may be maintained throughout the high exhaust system having been sufficiently described, the manner in which the specific illustrative apparatus may 100 vary the tension of high exhaust may now be considered.

It has been assumed for convenience in describing the manner in which the normal minimum tension of high exhaust is main- 105 tained that the abutment 363 comprising the movable board of pneumatic 364 is stationary and immovable. It is preferably through the agency of this pneumatic 364 and its capacity for moving the abutment 110 363 that the tension of high exhaust is varied when it is desired to have a greater tension available for operating the playing pneumatics.

The interior of the pneumatic 364 is connected with a source of exhaust, preferably regulated exhaust in the chest 12. There may be interposed in this connection a valve mechanism for opening the pneumatic 364 to atmosphere if and when it is desired to 115 render the pneumatic entirely inoperative except as a fixed abutment. A duct 365 leads from the pneumatic 364 to a valve chamber 366 having a port 367 to atmosphere, and a port 368 to an exhaust chamber 120 369. A duct 370 connects exhaust chamber 369 with the regulated pressure chest 12. A valve 371 is mounted in the valve chamber 366 and is controlled by a diaphragm 372 of a diaphragm chamber 373. The diaphragm 130

chamber 373 has a port 374 to atmosphere and is provided with the usual bleed passage to the exhaust chamber 369. Any suitable valve such as a slide valve 375 may be 5 provided to control the atmosphere port 374. The diaphragm chamber 373 may also be connected if desired, by a duct 376 with a vent in the tracker bar correspondingly numbered. A stop 377 may be provided to limit 10 the expanding movement of the bellows 364.

Assuming that atmosphere is present in the bellows 364 the position of the movable board 363 will be controlled by the differential between the pressure of atmosphere acting 15 upon its inner surface, and the pressure of high exhaust acting upon its outer surface. The resultant will be a force tending to hold the movable board 363 firmly against the stop 377. The differential between atmospheric pressure acting upon the outside of valve 358 and the pressure of high exhaust acting upon the inner surface of the valve plus the very light tension of the spring 362, tends to hold the spill-valve 358 20 in fixed relation with the atmosphere port 357. As the reservoir bellows collapses the stem 359 will impinge upon the movable board 363 of the pneumatic 364 and the resultant of the forces tending to close the 25 spill-valve will be opposed by the force tending to hold the movable board 363 in fixed position. The area of the movable board 363 may be so related to the area of the spill-valve and the tension of the spring 362 that 30 the force tending to hold the pneumatic 364 in an expanded position will entirely overcome the force tending to collapse the pneumatic. In this manner, when atmosphere is 35 present in the pneumatic 364, the movable board 363, forms to all intents and purposes, a fixed abutment, and in the manner previously described the normal minimum tension of high exhaust will be maintained with 40 substantial uniformity.

To vary the normal minimum tension of 45 high exhaust the operation of the spill-valve may be so controlled that it will not open to admit atmosphere through port 357 until a higher degree of exhaust has been attained 50 within the reservoir bellows. This may be conveniently accomplished by permitting the reservoir bellows to collapse to a greater extent before the spill-valve is opened thereby increasing indirectly the tension on the 55 spring. For this purpose, the position of the abutment 363 may be changed, preferably by means presently described.

If the movable board 363 of pneumatic 364 is drawn away from its stop 377, the reservoir bellows will of necessity collapse to a 60 greater extent before the spill-valve is opened to arrest its collapse. The spring 354 will thereby be elongated, to increase the force tending to expand the reservoir bellows. The 65 increased spring tension will govern a corre-

sponding increase in the degree of exhaust within the reservoir bellows.

Any suitable means may be provided for appropriately moving the abutment of the board 363 of the pneumatic 364. Herein the 70 pneumatic 364 is adapted to be exhausted to a greater or lesser degree through a connection with any suitable source of exhaust, preferably the regulated pressure chest 12. The regulated exhaust chest may be placed in 75 permanent communication with pneumatic 364 by opening atmosphere port 374 in the interposed valve mechanism and the consequent raising of the valve 371 by the action of regulated exhaust upon the diaphragm 372. 80

Under the control of the bellows board 33 and the regulating mechanism acting therethrough, the degree of regulated exhaust may be varied from a minimum which is only sufficient to sound notes with minimum intensity to a point where the degree of regulated exhaust will closely approximate or equal that of high exhaust. Under such conditions the valve 31 may be opened to restrict only to a very slight degree, if at 85 all, the communication between high exhaust chest 14 and regulated exhaust chest 12. The differential between the degree of exhaust within the pneumatic 364 and that within the reservoir bellows 351 will be 90 gradually decreased by the increase in regulated exhaust and as the degree of regulated exhaust more nearly approximates the degree of high exhaust the abutment 363 will oppose with a gradually diminishing force, 100 the force exerted through the valve stem 359 of the spill-valve 358. The area of the pneumatic 364 may be so related to the area of the valve 358 that the forces acting upon the abutment 363 and tending to move it 105 toward its stop, will predominate until the degree of regulated exhaust nearly equals that of high exhaust. The opposing force may then gradually overcome the force tending to hold the pneumatic 364 in expanded 110 position and inaugurate a collapsing movement of the pneumatic 364 to permit the reservoir bellows 351 to collapse to a greater extent before the spill-valve opens, thereby increasing the tension on the spring 354. 115 This, as heretofore explained, will govern an increase in the tension of high exhaust throughout the high exhaust system.

This increase in the degree of high exhaust acting upon the regulator valve may, even 120 if the valve is not wide open, slightly increase the degree of regulated exhaust, and such an increase being communicated to pneumatic 364 will decrease the differential between the pressures of regulated and high 125 exhaust acting upon opposite sides of the abutment 363. The initial increase in high exhaust will also increase the differential between the pressures of high exhaust and atmosphere acting upon opposite sides of valve 130

358 and tend to increase the force with which the stem 359 bears against the abutment 363. Under these circumstances a continuously progressive collapse of the pneumatic 364 may be inaugurated to govern a continuously progressive increase of tension in the high exhaust system. Assume for the purpose of illustration, that under the control of that part of the regulating mechanism acting through bellows 34, 35 and 36, it is desired to operate the striker pneumatics by regulated exhaust at a tension nearly approximating high exhaust. For this purpose atmosphere may be admitted to bellows 34 and 35 while regulated exhaust is present only in bellows 36. As previously described this results in relaxing the downward pull upon the board 33 and establishing a balancing equation for the control of valve 31 which will operate to maintain playing intensities at a relatively high level. With the degree of regulated exhaust so maintained the balance of forces tending to hold abutment 363 against its stop is disturbed, and a collapsing movement of the pneumatic 364 is inaugurated. This results in an increase in the tension of high exhaust in the chest 14 above the uniform nominal minimum. The pressure of high exhaust on the upper side of the valve 31 constituting a factor in the balancing equation controlling valve 31; the increase in high exhaust inaugurated by the described increase in regulated exhaust will tend to establish a new balancing equation to govern a further slight increase in the tension of regulated exhaust. The action just described may continue until the pneumatic 364 is completely collapsed and the degree of high exhaust increased to its maximum. The described increase in the degree of high exhaust may or may not produce an increase in regulated exhaust sufficient to cause an audible variation in playing intensities, depending upon the size of the regulator valve and the relative value of the force of high exhaust in the regulating balancing equation. Obviously, if atmosphere is admitted to bellows 34, 35 and 36 of the regulating mechanism and the valve 31 thereby opened wide, regulated exhaust will equal high exhaust and the maximum power of the instrument be rendered available for operating the playing pneumatics. Under such circumstances any purely regulating functions necessary to be performed may be transferred from the valve 31 to the reservoir bellows 351 which will then maintain regulated exhaust substantially uniform as it previously maintained high exhaust uniform and insure the maintenance of uniformity of playing whether one or many notes are sounded concurrently. For further illustration, assume that through the agency of that part of the reg-

ulating mechanism acting through bellows 37, it is desired to increase the degree of regulated exhaust for crescendo effect. For this purpose tracker duct 138 may be opened, with or without opening tracker 70 duct 139, depending upon the speed of crescendo desired. A collapse of pneumatic 101 is thereby inaugurated to govern an increase in the upward pull upon the bellows board 33 and valve 31. During this 75 operation the bellows 34, 35 and 36 or any of them may or may not contain regulated pressure, the presence or absence of regulated pressure in these bellows affecting merely the point in the scale of intensities 80 at which the crescendo operation commences. Preferably the bellows 37 is so proportioned that the pull exerted therethrough will predominate over the pull exerted through any one or all of the bellows 34, 35 and 36. 85 During the gradual increase in regulated exhaust governed by the increased upward pull through bellows 37 the differential between the pressures acting upon opposite sides of abutment 363 will be gradually 90 diminished until a collapsing movement of pneumatic 364 is started as in the case of regulated exhaust increase described in connection with bellows 34, 35 and 36. When the degree of regulated exhaust has been 95 sufficiently increased the degree of high exhaust will be increased as previously described and eventually when the regulating valve 31 is opened sufficiently to cause regulated exhaust to approximate or equal the 100 normal minimum degree of high exhaust the latter will be increased to its maximum and correspondingly increase regulated exhaust thereby rendering the maximum power of the instrument available for operating the playing pneumatics. 105 The reverse operation by which playing intensities are lowered and the degree of high exhaust returned to the normal minimum will be sufficiently clear to those 110 skilled in the art to obviate the necessity of a detailed description. 115 It will be observed from the foregoing description that when the regulating mechanism operating through valve 31 establishes a degree of regulated exhaust approaching the normal minimum degree of high exhaust the apparatus just described provides means for rendering available a greater tension of high exhaust. As described, this may be accomplished automatically whenever the increase is desirable, without the necessity of manual or tracker control. 120 If desired the apparatus for increasing the normal minimum tension of high exhaust may be rendered inoperative by the closing of port 374 by slide valve 375. The diaphragm chamber 373 would then be exhausted through its bleed passage, the valve 125 130

would drop to close the port 368 and to open atmosphere port 367 thereby admitting atmosphere to the interior of pneumatic 364.

5. If it is desired to place the apparatus for increasing the normal minimum degree of high exhaust under the control of the music sheet, a valve mechanism, tracker vent, and duct, may be provided to place the pneumatic 364 in communication with exhaust whenever the controlling tracker vent is open. This may conveniently be accomplished herein by means of the duct 376 opening to the diaphragm chamber 373.
10. Assuming that the slide valve 374 is closed, the valve 371 may be operated by the admission of atmosphere through tracker duct 376, and the pneumatic 364 is then placed in communication with regulated exhaust chest 12. Thereafter if the degree of regulated exhaust approximates the degree of high exhaust the pneumatic 364 will be operated as heretofore described.

It is to be understood that the invention 25 is not limited to the particular construction, organization and mode of operation shown in the drawings and described above for illustration. On the contrary, the invention may be variously embodied and the illustrative construction variously modified within the scope of the subjoined claims.

I claim as my invention:

1. In an instrument of the character described and having playing pneumatics, a main source of power for operating said pneumatics and regulating means interposed therebetween; a governor bellows operatively connected to said main source of power; resilient means tending to hold said bellows in expanded position; an atmosphere port to said bellows; means to open said port when a predetermined degree of exhaust has been established in said bellows; and means responsive to variations in regulated 40 tension for delaying the effective opening of said port until a higher degree of exhaust has been established in said bellows.

2. In an instrument of the character described and having playing pneumatics, a main source of power for operating said pneumatics and regulating means interposed therebetween; a governor bellows operatively connected to said main source of power; resilient means tending to hold said bellows in expanded position; an atmosphere port to said bellows; means to open said port when a predetermined degree of exhaust has been established in said bellows; and automatically operable means responsive to variations in regulated tension for delaying the effective opening of said port until a greater degree of tension has been established in said bellows.

3. In an instrument of the character described and having playing pneumatics, a

main source of power for operating said pneumatics and regulating means interposed therebetween; a governor bellows operatively connected to said main source of power; resilient means tending to hold said bellows in expanded position; an atmosphere port to said bellows; means to open said port when a predetermined degree of exhaust has been established in said bellows; a tracker; and tracker controllable means normally responsive to variations in regulated tension for delaying the effective opening of said port until a greater degree of tension has been established in said bellows.

4. In an instrument of the character described and having playing pneumatics, a main source of power for operating said pneumatics and regulating means interposed therebetween; a governor bellows operatively connected to said main source of power; resilient means tending to hold said bellows in expanded position; an atmosphere port to said bellows; a valve for said port; means to open said valve upon collapse of said governor bellows; and means responsive to variations in regulated tension for changing the position of said valve opening means relatively to the movable board of said governor bellows.

5. In an instrument of the character described and having playing pneumatics, a main source of power for operating said pneumatics and regulating means interposed therebetween; a governor bellows operatively connected to said main source of power; resilient means tending to hold said bellows in expanded position; an atmosphere port to said bellows; a valve for said port; means to open said valve upon collapse of said governor bellows; and automatic means responsive to variations in regulated tension for changing the position of said valve opening means relatively to the movable board of said governor bellows.

6. In an instrument of the character described and having playing pneumatics, a main source of power for operating said pneumatics and regulating means interposed therebetween; a governor bellows operatively connected to said main source of power; resilient means tending to hold said bellows in expanded position; an atmosphere port to said bellows; a valve for said port; means to open said valve upon collapse of said governor bellows; and manually controllable means normally responsive to variations in regulated tension for changing the position of said valve opening means relatively to the movable board of said governor bellows.

7. In an instrument of the character described and having playing pneumatics, a main source of power for operating said pneumatics and regulating means interposed therebetween; a governor bellows opera-

tively connected to said main source of power; resilient means tending to hold said bellows in expanded position; an atmosphere port to said bellows; a valve for said port; means to open said valve upon collapse of said governor bellows; a tracker; and tracker controllable means normally responsive to variations in regulated tension for changing the position of said valve opening means relatively to the movable board of said governor bellows.

8. In an instrument of the character described and having playing pneumatics; a main source of power for operating said pneumatics and regulating means interposed therebetween; a governor bellows operatively connected to said source of power; resilient means tending to hold said bellows in expanded position; an atmosphere port to said bellows; a valve for said port; means to open said valve upon collapse of said governor bellows; and automatic pneumatic means responsive to variations in regulated tension for changing the position of said valve opening means relatively to the movable board of said governor bellows.

9. In an instrument of the character described and having playing pneumatics, a main source of power for operating said pneumatics and regulating means interposed therebetween; a governor bellows operatively connected to said main source of power; resilient means tending to hold said bellows in expanded position; an atmosphere port to said bellows; a valve for said port; means to open said valve upon collapse of said governor bellows; and manually controllable pneumatic means normally responsive to variations in regulated tension for changing the position of said valve opening means relatively to the movable board of said governor bellows.

10. In an instrument of the character described and having playing pneumatics, a main source of power for operating said pneumatics and regulating means interposed therebetween; a governor bellows with relatively movable walls operatively connected to said main source of power; an atmosphere port in one of said walls; a valve for said port; means operatively related to the other wall for opening said valve; and means responsive to variations in regulated tension for changing the relation of said valve opening means to said atmosphere port.

11. In an instrument of the character described and having playing pneumatics, a main source of power for operating said pneumatics and regulating means interposed therebetween; a governor bellows with relatively movable walls operatively connected to said main source of power; an atmosphere port in one of said walls; a valve for said port; means operatively related to the other wall for opening said valve; and pneumatic

means responsive to variations in regulated tension for changing the relation of said valve opening means to said atmosphere port.

12. In an instrument of the character described and having playing pneumatics, a main source of power for operating said pneumatics and regulating means interposed therebetween; a governor bellows with relatively movable walls operatively connected to said main source of power; an atmosphere port in one of said walls; a valve for said port; means operatively related to the other wall for opening said valve; and automatic pneumatic means responsive to variations in regulated tension for changing the relation of said valve opening means to said atmosphere port.

13. In an instrument of the character described and having playing pneumatics, a main source of power for operating said pneumatics and regulating means interposed therebetween; a governor bellows with relatively movable walls operatively connected to said main source of power; an atmosphere port in one of said walls; a valve for said port; means operatively related to the other wall for opening said valve; and manually controllable pneumatic means normally responsive to variations in regulated tension for changing the relation of said valve opening means to said atmosphere port.

14. In an instrument of the character described and having playing pneumatics, a main source of power for operating said pneumatics and regulating means interposed therebetween; a governor bellows with relatively movable walls operatively connected to said main source of power; an atmosphere port in one of said walls; a valve for said port; means operatively related to the other wall for opening said valve; and manually controllable means normally responsive to variations in regulated tension for changing the relation of said valve opening means to said atmosphere port.

15. In an instrument of the character described and having playing pneumatics, a main source of power for operating said pneumatics and regulating means interposed therebetween; a governor bellows with relatively movable walls operatively connected to said main source of power; an atmosphere port in one of said walls; a valve for said port; means operatively related to the other wall for opening said valve; a tracker; and tracker controllable means normally responsive to variations in regulated tension for changing the relation of said valve opening means to said atmosphere port.

16. In an instrument of the character described and having playing pneumatics, a main source of power for operating said pneumatics and regulating means interposed therebetween; a governor bellows operatively connected to said main source of power

- and including, a movable board, resilient means tending to hold said bellows in expanded position, an atmosphere port in said movable board, a valve for said port mounted upon a valve stem, an abutment for the valve stem mounted upon the fixed board, and means to change the position of said abutment to vary the operation of the governor bellows.
17. In an instrument of the character described and having playing pneumatics, a main source of power for operating said pneumatics and regulating means interposed therebetween; a governor bellows operatively connected to said main source of power and including, a movable board, resilient means tending to hold said bellows in expanded position, an atmosphere port in said movable board, a valve for said port mounted upon a valve stem, an abutment for the valve stem mounted upon the fixed board, and automatic pneumatic means to change the position of said abutment to vary the operation of the governor bellows.
18. In an instrument of the character described and having playing pneumatics, a main source of power for operating said pneumatics and regulating means interposed therebetween; a governor bellows operatively connected to said main source of power and including, a movable board, resilient means tending to hold said bellows in expanded position, an atmosphere port in said movable board, a valve for said port mounted upon a valve stem, an abutment for the valve stem mounted upon the fixed board, and manually controlled means to change the position of said abutment to vary the operation of the governor bellows.
19. In an instrument of the character described and having playing pneumatics, a main source of power for operating said pneumatics and regulating means interposed therebetween; a governor bellows operatively connected to said main source of power and including, a movable board, resilient means tending to hold said bellows in expanded position, an atmosphere port in said movable board, a valve for said port mounted upon a valve stem, an abutment for the valve stem mounted upon the fixed board, and manually controlled pneumatic means to change the position of said abutment to vary the operation of the governor bellows.
20. In an instrument of the character described and having playing pneumatics, a main source of power for operating said pneumatics and regulating means interposed therebetween; a governor bellows operatively connected to said main source of power and including, a movable board, resilient means tending to hold said bellows in expanded position, an atmosphere port in said movable board, a valve for said port mounted upon a valve stem, an abutment for the valve stem mounted upon the fixed board, and means to change the position of said abutment to vary the operation of the governor bellows.
21. In an instrument of the character described and having playing pneumatics, a main source of power for operating said pneumatics and regulating means interposed therebetween; a governor bellows operatively connected to said main source of power and including, a movable board, resilient means tending to hold said bellows in expanded position, an atmosphere port in said movable board, a valve for said port mounted upon a valve stem, an abutment for the valve stem mounted upon the fixed board, and pneumatic means to change the position of said abutment to vary the operation of the governor bellows.
22. In an instrument of the character described and having playing pneumatics, a main source of power for operating said pneumatics and regulating means interposed therebetween; a governor bellows operatively connected to said main source of power and including, a movable board, resilient means tending to hold said bellows in expanded position, an atmosphere port to said bellows; a valve in said port, a valve stem extending into said reservoir bellows, a pneumatic within said governor bellows having its movable board in the path of said valve stem, and means to introduce exhaust to said pneumatic to vary the position of its movable board and thereby vary the operation of said governor bellows.
23. In an instrument of the character described and having playing pneumatics, a main source of power for operating said pneumatics and regulating means interposed therebetween; a governor bellows operatively connected to said main source of power and including, a movable board, resilient means tending to hold said bellows in expanded position, an atmosphere port to said bellows, a valve in said port, a valve stem extending into said reservoir bellows, a pneumatic within said governor bellows having its movable board in the path of said valve stem, an automatically operable means to introduce exhaust to said pneumatic to vary the position of its movable board and thereby vary the operation of said governor bellows.
24. In an instrument of the character described and having playing pneumatics, a main source of power for operating said pneumatics and regulating means interposed therebetween; a governor bellows operatively connected to said main source of power and including, a movable board, resilient means tending to hold said bellows in expanded position, an atmosphere port to said movable board, a valve for said port

5 said bellows, a valve in said port, a valve stem extending into said reservoir bellows, a pneumatic within said governor bellows having its movable board in the path of said 10 valve stem, and manually controlled means to introduce exhaust to said pneumatic to vary the position of its movable board and thereby vary the operation of said governor bellows.

10 25. In an instrument of the character described and having playing pneumatics, a main source of power for operating said pneumatics and regulating means interposed therebetween; a governor bellows operatively connected to said main source of power and including, a movable board, resilient means tending to hold said bellows in expanded position, an atmosphere port to said bellows, a valve in said port, a valve 15 stem extending into said reservoir bellows, a pneumatic within said governor bellows having its movable board in the path of said valve stem, a tracker, and tracker controlled means to introduce exhaust to said pneumatic to vary the position of its movable board and thereby vary the operation of said governor bellows.

20 26. An instrument of the character described comprising, in combination, playing pneumatics; a main source of power for operating said playing pneumatics; a valve between said main source of power and a regulated wind chest connected to said playing pneumatics; means operatively connected to said main source of power for normally maintaining substantial uniformity of pressure therein; means connected to said valve for maintaining uniformity of pressure in said regulated wind chest at predetermined levels; and means operatively connected with said regulated wind chest to vary the degree of exhaust of the main source of power upon the establishment of a predetermined pressure in the regulated wind 25 chest.

30 27. An instrument of the character described comprising, in combination, playing pneumatics; a main source of power for operating said playing pneumatics; means for maintaining a substantially uniform pressure at the main source of power; a regulated wind chest connected to said playing pneumatics; means controlling communication between said main source of power and said regulated wind chest having the capacity of varying the degree of pressure in said regulated wind chest and maintaining any given pressure therein; means operatively connected with said regulated wind 35 chest and said high exhaust pressure maintaining means to increase the normal pressure at the main source of power whenever the degree of regulated pressure approximates that of high exhaust.

40 28. An instrument of the character de-

scribed comprising, in combination, playing pneumatics; a main source of power for operating said playing pneumatics; expression governing mechanism operatively interposed between said main source of power and the playing pneumatics to vary playing intensities; means to maintain a substantially uniform tension at the main source of power; and means to increase the normal tension of the main source of power when the expression governing means tends to increase playing intensities to approximate an intensity determinable by the normal tension of the main source of power.

45 29. An instrument of the character described comprising, in combination, playing pneumatics; a main source of power for operating said playing pneumatics; means to maintain a substantially uniform normal pressure at the main source of power; expression governing means operatively interposed between the main source of power and the playing pneumatics for varying playing intensities from a predetermined minimum to a maximum dependent upon the normal pressure of the main source of power; and means to vary the normal pressure of the main source of power for further varying playing intensities.

50 30. An instrument of the character described comprising, in combination, playing pneumatics; a main source of power for operating said playing pneumatics; means to maintain a substantially uniform normal pressure at the main source of power; expression governing means operatively interposed between the main source of power and the playing pneumatics for varying playing intensities from a predetermined minimum to a maximum dependent upon the normal pressure of the main source of power; and automatic means to vary the normal pressure of the main source of power for further varying playing intensities.

55 31. An instrument of the character described comprising, in combination, playing pneumatics; a main source of power for operating said playing pneumatics; means to maintain a substantially uniform normal pressure at the main source of power; expression governing means operatively interposed between the main source of power and the playing pneumatics for automatically varying playing intensities from a predetermined minimum to a maximum dependent upon the normal pressure of the main source of power; and means to vary the normal pressure of the main source of power for further varying playing intensities.

60 32. An instrument of the character described comprising, in combination, playing pneumatics; a main source of power for operating said playing pneumatics; means to maintain a substantially uniform normal pressure at the main source of power; ex-

125 130

- pression governing means operatively interposed between the main source of power and the playing pneumatics for automatically varying playing intensities from a pre-determined minimum to a maximum dependent upon the normal pressure of the main source of power; and automatic pneumatic means to vary the normal pressure of the main source of power for further varying playing intensities.
33. An instrument of the character described comprising, in combination, playing pneumatics; a main source of power for operating said playing pneumatics; a regulated wind chest; means to connect the playing pneumatics selectively to said regulated wind chest; a high exhaust wind chest; regulating means operatively interposed between said wind chests; means to maintain a normal uniform pressure in the high exhaust wind chests; and means operatively connected with the regulated exhaust wind chest to increase the tension of high exhaust when the tension of regulated exhaust approximates the tension of the normal high exhaust and thereafter further increase the tension of regulated exhaust.
34. An instrument of the character described comprising, in combination, playing pneumatics; a main source of power for operating said playing pneumatics; expression regulating and varying means interposed between the main source of power and the playing pneumatics; and supplementary expression varying means acting upon said main source of power.
35. An instrument of the character described comprising, in combination, playing pneumatics; a main source of power for operating said playing pneumatics; and two expression governing means, one operatively interposed between the main source of power and the playing pneumatics, and the other adapted to vary the pressure of the main source of power.
36. An instrument of the character described comprising, in combination, playing pneumatics; a regulated wind chest for said playing pneumatics; a main source of power for operating said playing pneumatics; expression governing and varying means operatively interposed between said main source of power and said regulated wind chest; means for normally maintaining a uniform pressure at said main source of power; means for varying the pressure at said main source of power; and manually controlled means to connect said last named means with said regulated wind chest.
37. An instrument of the character described comprising, in combination, playing pneumatics; a regulated wind chest for said playing pneumatics; a main source of power for operating said playing pneumatics; expression governing and varying means operatively interposed between said main source of power and said regulated wind chest; means for normally maintaining a uniform pressure at said main source of power; means for varying the pressure at said main source of power; and manually controlled means to connect said last named means with said regulated wind chest.
38. An instrument of the character described comprising, in combination, playing pneumatics; a regulated wind chest for said playing pneumatics; a main source of power for operating said playing pneumatics; expression governing and varying means operatively interposed between said main source of power and said regulated wind chest; means for normally maintaining a uniform pressure at said main source of power; automatic pneumatic means for varying the pressure at said main source of power; and manually controlled means to connect said last named means with said regulated wind chest.
39. An instrument of the character described comprising, in combination, playing pneumatics; a regulated wind chest for said playing pneumatics; a main source of power for operating said playing pneumatics; expression governing and varying means operatively interposed between said main source of power and said regulated wind chest; a governor bellows operatively connected to said main source of power; means for tensioning said governor bellows; means to maintain said tension substantially uniform; pneumatic means to vary said tension to vary the degree of pressure at said main source of power; and manually controlled means to connect said last named means with said regulated wind chest.
40. An instrument of the character described comprising, in combination, playing pneumatics; a regulated wind chest for said playing pneumatics; a main source of power for operating said playing pneumatics; expression governing and varying means operatively interposed between said main source of power and said regulated wind chest; a governor bellows operatively connected to said main source of power; resilient means tending to hold said bellows in expanded position; means providing an atmosphere port to said bellows; means to open said port when a predetermined degree of exhaust has been established in said bellows; pneumatic means to delay the effective opening of said port until a higher degree of exhaust has been established in said bellows; and manually controlled means to connect said last named means with said regulated wind chest.
41. An instrument of the character described comprising, in combination, playing pneumatics; a regulated wind chest for said playing pneumatics; a main source of power

power for operating said playing pneumatics; expression governing and varying means operatively interposed between said main source of power and said regulated wind chest; a governor bellows operatively connected to said main source of power; resilient means tending to hold said bellows in expanded position; means providing an atmosphere port to said bellows; a valve for 5 said port; means to open said valve upon collapse of said governor bellows; pneumatic means to change the position of said valve opening means relatively to the movable board of said governor bellows; and 10 manually controlled means to connect said last named means with said regulated wind chest.

42. An instrument of the character described comprising, in combination, playing pneumatics; a regulated wind chest for said playing pneumatics; a main source of power for operating said playing pneumatics; expression governing and varying means operatively interposed between said main source 20 of power and said regulated wind chest; a governor bellows with relatively movable walls operatively connected to said main source of power; means providing an atmosphere port in one of said walls; a valve for 25 said port; means operatively related to the other wall for opening said valve; pneumatic means to vary the relation of said valve opening means to said atmosphere port; and manually controlled means to connect said last named means with said regulated wind chest.

43. An instrument of the character described comprising, in combination, playing pneumatics; a regulated wind chest for 30 said playing pneumatics; a main source of power for operating said playing pneumatics; expression governing and varying means operatively interposed between said main source of power and said regulated wind chest; a governor bellows operatively connected to said main source of power and including, a movable board, resilient means tending to hold said bellows in expanded position, means providing an atmosphere port 35 in said movable board, a valve for said port mounted upon a valve stem; an abutment mounted upon a fixed board; pneumatic means to change the position of said abutment to vary the operation of the governor bellows; and manually controlled means to connect said last named means with said regulated wind chest.

44. An instrument of the character described comprising, in combination, playing pneumatics; a regulated wind chest for said playing pneumatics; a main source of power for operating said playing pneumatics; expression governing and varying means operatively interposed between said main source 45 of power and said regulated wind chest; a

governor bellows operatively connected to said main source of power and including, a movable board, resilient means tending to hold said bellows in expanded position, means providing an atmosphere port in said movable board, a valve for said port; a valve stem extending into said governor bellows; a pneumatic within said governor bellows having its movable board in the path of said valve stem; and manually controlled 50 means to introduce regulated exhaust to said pneumatic to vary the position of its movable board and thereby vary the operation of said governor bellows.

45. An instrument of the character described comprising, in combination, playing pneumatics; a regulated wind chest for said playing pneumatics; a main source of power for operating said playing pneumatics; expression governing and varying means operatively interposed between said main source of power and said regulated wind chest; means for normally maintaining a uniform 55 pressure at said main source of power; means for varying the pressure at said main source of power; a tracker; and tracker controlled means to connect said last named means with said regulated wind chest.

46. An instrument of the character described comprising, in combination, playing pneumatics; a regulated wind chest for said playing pneumatics; a main source of power for operating said playing pneumatics; expression governing and varying means operatively interposed between said main 60 source of power and said regulated wind chest; means for normally maintaining a uniform pressure at said main source of power; pneumatic means for varying the pressure at said main source of power; a tracker; and tracker controlled means to connect said last named means with said regulated wind chest.

47. An instrument of the character described comprising, in combination, playing pneumatics; a regulated wind chest for said playing pneumatics; a main source of power for operating said playing pneumatics; expression governing and varying means operatively interposed between said main 65 source of power and said regulated wind chest; means for normally maintaining a uniform pressure at said main source of power; automatic pneumatic means for varying the pressure at said main source of power; a tracker; and tracker controlled means to connect said last named means with said regulated wind chest.

48. An instrument of the character described comprising, in combination, playing pneumatics; a regulated wind chest for said playing pneumatics; a main source of power for operating said playing pneumatics; expression governing and varying means operatively interposed between said main 70 source of power and said regulated wind chest;

- source of power and said regulated wind chest; a governor bellows operatively connected to said main source of power; means for tensioning said governor bellows; 5 means to maintain said tension substantially uniform; pneumatic means to vary said tension to vary the degree of pressure at said main source of power; a tracker; and tracker controlled means to connect said last named 10 means with said regulated wind chest.
49. An instrument of the character described comprising, in combination, playing pneumatics; a regulated wind chest for said playing pneumatics; a main source of power 15 for operating said playing pneumatics; expression governing and varying means operatively interposed between said main source of power and said regulated wind chest; a governor bellows operatively connected to said main source of power; resilient means tending to hold said bellows in expanded position; means providing an atmosphere port in said movable board, a valve for said port mounted upon a valve stem; an abutment mounted upon a fixed board, pneumatic means to change the position of said abutment to vary the operation of the governor bellows; a tracker; and tracker controlled means to connect said last named 20 means with said regulated wind chest.
50. An instrument of the character described comprising, in combination, playing pneumatics; a regulated wind chest for said 25 playing pneumatics; a main source of power for operating said playing pneumatics; expression governing and varying means operatively interposed between said main source of power and said regulated wind chest; a governor bellows operatively connected to said main source of power; resilient means tending to hold said bellows in expanded position; means providing an atmosphere port to said bellows; a valve for 30 said port; means to open said valve upon collapse of said governor bellows; pneumatic means to change the position of said valve opening means relatively to the movable board of said governor bellows; a 35 tracker; and tracker controlled means to connect said last named means with said regulated wind chest.
51. An instrument of the character described comprising, in combination, playing pneumatics; a regulated wind chest for said 40 playing pneumatics; a main source of power for operating said playing pneumatics; expression governing and varying means operatively interposed between said main 45 source of power and said regulated wind chest; a governor bellows with relatively movable walls operatively connected to said main source of power; means providing an atmosphere port in one of said walls; a 50 valve for said port; means operatively re- lated to the other wall for opening said valve; pneumatic means to vary the relation of said valve opening means to said atmosphere port; a tracker; and tracker controlled means to connect said last named 55 means with said regulated wind chest.
52. An instrument of the character described comprising, in combination, playing pneumatics; a regulated wind chest for said playing pneumatics; a main source of power 60 for operating said playing pneumatics; expression governing and varying means operatively interposed between said main source of power and said regulated wind chest; a governor bellows operatively connected to said main source of power and including, a movable board, resilient means tending to hold said bellows in expanded position, means providing an atmosphere port in said movable board, a valve for said 65 port mounted upon a valve stem; an abutment mounted upon a fixed board, pneumatic means to change the position of said abutment to vary the operation of the governor bellows; a tracker; and tracker controlled means to connect said last named 70 means with said regulated wind chest.
53. An instrument of the character described comprising, in combination, playing pneumatics; a regulated wind chest for said 75 playing pneumatics; a main source of power for operating said playing pneumatics; expression governing and varying means operatively interposed between said main source of power and said regulated wind 80 chest; a governor bellows operatively connected to said main source of power and including, a movable board, resilient means tending to hold said bellows in expanded position, means providing an atmosphere port in said movable board, a valve for said 85 port mounted upon a valve stem; an abutment mounted upon a fixed board, pneumatic means to change the position of said abutment to vary the operation of the governor bellows; a tracker; and tracker controlled means to connect said last named 90 means with said regulated wind chest.
54. An instrument of the character described comprising, in combination, playing pneumatics; a main source of power for operating said playing pneumatics; a high exhaust wind chest communicating with said 95 main source of power; a regulated exhaust wind chest communicating with said playing pneumatics; expression governing and varying means including a throttle valve controlling a port between said wind chests 100 and adapted to be opened in the direction of the pressure of regulated exhaust; means to maintain a normally uniform pressure of high exhaust; and means to vary said pressure to vary regulation by said throttle valve. 105

55. An instrument of the character described comprising, in combination, playing pneumatics; a main source of power for operating said playing pneumatics; a high exhaust wind chest communicating with said main source of power; a regulated exhaust wind chest communicating with said playing pneumatics; expression governing and varying means including, a throttle valve controlling a port between said wind chests and adapted to be opened in the direction of the pressure of regulated exhaust; means to maintain a normally uniform pressure of high exhaust; and means to increase the degree of exhaust at said main source of power to increase the forces tending to open said throttle valve. 70
56. An instrument of the character described comprising, in combination, playing pneumatics; a main source of power for operating said playing pneumatics; a high exhaust wind chest communicating with said main source of power; a regulated exhaust wind chest communicating with said playing pneumatics; expression governing and varying means including, a throttle valve controlling a port between said wind chests and adapted to be opened in the direction of the pressure of regulated exhaust; means to normally maintaining a uniform pressure at said main source of power; and pneumatic means for varying the pressure at said main source of power. 80
57. An instrument of the character described comprising, in combination, playing pneumatics; a main source of power for operating said playing pneumatics; a high exhaust wind chest communicating with said main source of power; a regulated exhaust wind chest communicating with said playing pneumatics; expression governing and varying means including a throttle valve controlling a port between said wind chests and adapted to be opened in the direction of the pressure of regulated exhaust; means for normally maintaining a uniform pressure at said main source of power; and pneumatic means for varying the pressure at said main source of power. 85
58. An instrument of the character described comprising, in combination, playing pneumatics; a main source of power for operating said playing pneumatics; a high exhaust wind chest communicating with said main source of power; a regulated exhaust wind chest communicating with said playing pneumatics; expression governing and varying means including a throttle valve controlling a port between said wind chests and adapted to be opened in the direction of the pressure of regulated exhaust; means for normally maintaining a uniform pressure at said main source of power; and manually controlled means to connect said last named means with said regulated wind chest. 90
59. An instrument of the character described comprising, in combination, playing pneumatics; a main source of power for operating said playing pneumatics; a high exhaust wind chest communicating with said main source of power; a regulated exhaust wind chest communicating with said playing pneumatics; expression governing and varying means including a throttle valve controlling a port between said wind chests and adapted to be opened in the direction of the pressure of regulated exhaust; a governor bellows operatively connected to said main source of power; means for tensioning said governor bellows; means to maintain said tension substantially uniform; and means to vary said tension to vary the degree of pressure at said main source of power. 95
60. An instrument of the character described comprising, in combination, playing pneumatics; a main source of power for operating said playing pneumatics; a high exhaust wind chest communicating with said main source of power; a regulated exhaust wind chest communicating with said playing pneumatics; expression governing and varying means including a throttle valve controlling a port between said wind chests and adapted to be opened in the direction of the pressure of regulated exhaust; a governor bellows operatively connected to said main source of power; resilient means tending to hold said bellows in expanded position; means providing an atmosphere port to said bellows; a valve for said port; means to open said valve upon collapse of said governor bellows; and means to change the position of said valve opening means relatively to the movable board of said governor bellows. 100
61. An instrument of the character described comprising, in combination, playing pneumatics; a main source of power for operating said playing pneumatics; a high exhaust wind chest communicating with said main source of power; a regulated exhaust wind chest communicating with said playing pneumatics; expression governing and varying means including a throttle valve controlling a port between said wind chests and adapted to be opened in the direction of the pressure of regulated exhaust; a governor bellows operatively connected to said main source of power and including a movable board, resilient means tending to hold said bellows in expanded position, means providing an atmosphere port in said movable board, a valve for said port mounted upon a valve stem; an abutment mounted upon a fixed board; and means to change the 110
62. An instrument of the character described comprising, in combination, playing pneumatics; a main source of power for operating said playing pneumatics; a high exhaust wind chest communicating with said main source of power; a regulated exhaust wind chest communicating with said playing pneumatics; expression governing and varying means including a throttle valve controlling a port between said wind chests and adapted to be opened in the direction of the pressure of regulated exhaust; a governor bellows operatively connected to said main source of power and including a movable board, resilient means tending to hold said bellows in expanded position, means providing an atmosphere port in said movable board, a valve for said port mounted upon a valve stem; an abutment mounted upon a fixed board; and means to change the 120
63. An instrument of the character described comprising, in combination, playing pneumatics; a main source of power for operating said playing pneumatics; a high exhaust wind chest communicating with said main source of power; a regulated exhaust wind chest communicating with said playing pneumatics; expression governing and varying means including a throttle valve controlling a port between said wind chests and adapted to be opened in the direction of the pressure of regulated exhaust; a governor bellows operatively connected to said main source of power and including a movable board, resilient means tending to hold said bellows in expanded position, means providing an atmosphere port in said movable board, a valve for said port mounted upon a valve stem; an abutment mounted upon a fixed board; and means to change the 130

position of said abutment to vary the operation of said governor bellows.

62. An instrument of the character described comprising, in combination, playing pneumatics; a main source of power for operating said playing pneumatics; a high exhaust wind chest communicating with said main source of power; a regulated wind chest communicating with said playing pneumatics; expression governing and varying means including a throttle valve controlling a port between said wind chests and adapted to be opened in the direction of the pressure of regulated exhaust; a governor bellows operatively connected to said main source of power and including a movable board, resilient means tending to hold said bellows in expanded position, means providing an atmosphere port in said movable board, a valve for said port mounted upon a valve stem; an abutment mounted upon a fixed board; and pneumatic means to change the position of said abutment to vary the operation of said governor bellows.
63. An instrument of the character described comprising, in combination, playing pneumatics; a main source of power for operating said playing pneumatics; a high exhaust wind chest communicating with said main source of power; a regulated wind chest communicating with said playing pneumatics; expression governing and varying means including a throttle valve controlling a port between said wind chests and adapted to be opened in the direction of the pressure of regulated exhaust; a governor bellows operatively connected to said main source of power and including a movable board, resilient means tending to hold said

bellows in expanded position, means providing an atmosphere port in said movable board, a valve for said port mounted upon a valve stem; an abutment mounted upon a fixed board; pneumatic means to change the position of said abutment to vary the operation of said governor bellows; and manually controlled means to connect last named means with said regulated wind chest.

64. An instrument of the character described comprising, in combination, playing pneumatics; a main source of power for operating said playing pneumatics; a high exhaust wind chest communicating with said main source of power; a regulated wind chest communicating with said playing pneumatics; expression governing and varying means including a throttle valve controlling a port between said wind chests and adapted to be opened in the direction of the pressure of regulated exhaust; a governor bellows operatively connected to said main source of power and including a movable board, resilient means tending to hold said bellows in expanded position, means providing an atmosphere port in said movable board, a valve for said port mounted upon a valve stem; an abutment mounted upon a fixed board; pneumatic means to change the position of said abutment to vary the operation of said governor bellows; a tracker; and tracker controlled means to connect last named means with said regulated wind chest.

In testimony whereof, I have signed my name to this specification this 28th day of March, 1917.

CHARLES F. STODDARD.
